UNITED STATES PATENT OFFICE.

STANLEY WALTER YARDER, OF TOLEDO, OHIO.

TOOL-BOX TRAY AND PARTITION THEREFOR.

Application filed March 4, 1926. Serial No. 92,320.

This invention relates to tool boxes and more particularly to trays therefor.

The invention has for one of its objects to provide a tool box tray involving a construction adapted to permit partitions to be readily arranged therein when dividing it up into tool receiving compartments of the desired number and size, the invention comprehending a tray provided in its bottom 10 with longitudinally and transversely extending intersecting grooves for the reception of the lower edges of the partitions.

A further object of the invention is to provide partitions that may be readily placed in the grooves and secured to the tray, the invention comprehending in this connection sheet metal partitions of hollow formation and provided with laterally directed lower edge portions adapted to be 20 positioned in the grooves and secured to the bottom of the tray.

With the foregoing and other objects in view, the invention consists of the novel construction hereinafter fully described and 25 claimed, and illustrated in the accompanying drawing, wherein:

Figure 1 is a top plan view of a tool box tray embodying my invention.

Figure 2 is a detail sectional view taken 30 on the plane indicated by the line 2—2 of Figure 1.

Figure 3 is a similar view taken on the plane indicated by the line 3—3 of Figure 1.

Figure 4 is a sectional view taken on a 35 plane extending vertically and centrally through a tool box equipped with trays constructed in accordance with my invention, and

Figure 5 is a detail perspective view of one 40 of the tray partitions.

Corresponding and like parts are referred to in the following description, and designated in the several views of the accompanying drawing, by similar reference characters.

In the drawing, 1 designates the body and 45 2 the lid of a sheet metal tool box. A handle 3 is pivoted as at 4 to the lid 2, and the bottom portion of the body 1 is divided up into compartments 6 and 7 by partitions 8 and 9.

A bottom tray 10 and top tray 11 are 50 removably arranged within the body 1, the former being supported by the partitions 8 and 9 and the latter by flanges 12 resting upon the upper edges of certain sides of the body.

In accordance with the present invention 55 each of the trays 10 and 11 is provided in its bottom with transversely extending grooves 13 and a longitudinally extending groove 14. The grooves 13 and 14 intersect each other and the latter is arranged at the longitudinal center of the tray. The tray is made of sheet metal, and the grooves 13 and 14 are provided by downwardly offsetting portions of the bottom thereof. The partitions 15 are also made of sheet metal 60 and are of hollow formation with the lower edge portions thereof deflected outwardly to provide flanges 16. The flanges 16 fit in the grooves 13 and 14 and their outer edges contact with the side walls of the grooves. The 70 partitions 15 may be secured in place by spot welding or in any other suitable manner, and one of them, preferably the one extending longitudinally of the tray, is provided with a grip 17 through the medium 75 of which the tray may be lifted from or placed in the box. The grip 17 is of substantially cylindrical formation and is applied to the upper edge of the partition in the manner shown in Figure 3. It may be 80 secured in place by welding or in any other suitable manner.

The tray may be provided with any number of the partitions 15, the number used depending solely upon the number of compartments the tray is to be divided up into. The tray 10 is shown as being provided with three compartments, and to provide these compartments one longitudinal partition and one transverse partition are employed. The 85 tray 11 is shown as provided with eight compartments, and to provide these compartments six transverse partitions and one longitudinal partition are employed. In each tray the grip 17 is located at the center 90 so as to prevent the tilting of the tray during its removal from or replacement in the box. The trays, partitions and grips may be readily stamped up from light sheet metal, and the provision of the bottoms of 100 the trays with the grooves not only facilitate the arrangement of the partitions but also strengthens and reinforces the trays.

It should be understood that the drawing is merely illustrative and does not pretend to give exact proportions. Furthermore, the said drawing is illustrative of a preferred construction, it being my expectation that 105

various changes and modifications may be made without departing from the spirit and scope of my invention.

What is claimed is:—

- 5 1. A sheet metal tray having the bottom thereof provided with grooves, and hollow sheet metal partitions having their lower edge portions laterally deflected to provide flanges, said flanges being positioned within

the grooves and secured to the bottom of the 10 tray.

2. A metal tray having the bottom thereof provided with a groove, and a metal partition having a laterally enlarged lower portion fitting in the groove and secured to the 15 bottom of the tray.

In testimony whereof I affix my signature.
STANLEY WALTER YARDER.
